UNITED STATES PATENT OFFICE

2,433,693

MOTOR RAIL

Jawn R. Hall, San Jose, Calif., assignor of eighty-five per cent to Richard H. Drew, San Jose, Calif.

Application November 26, 1945, Serial No. 630,891

2 Claims. (Cl. 248—19)

1

The present invention relates particularly to that type of devices used in mounting motors in operative position relative to the work they are to perform.

It is the object of this invention to provide a motor rail for the purpose indicated that will permit a motor to be mounted in any desired position, be it horizontal or vertical or at any angle between the two positions.

It is also an object to provide a device of the character indicated that will be economical to manufacture, strong and durable, and highly efficient in its practical application.

In the drawing:

Figure 1 is an isometric perspective of one element embodying my invention, part being broken away.

Figure 2 is a perspective view of the other element embodying my invention, partly broken away.

Figure 3 is a sectional view on line 3—3 of Figure 1.

Referring now more specifically to the drawing, I show at 1 an element designed for mounting in any desired position through the medium of slots as at 2 and suitable bolts not shown. The end portions of this element are turned outwardly as shown at 3 and 4, thence into parallel relation with the main body portion as at 5 and 6, thence backwardly into parallel relation with the parts 3 and 4 as shown at 7 and 8. The portions 3 and 4 have holes formed in their centers as at 9 and 10, and the part 8 has a hole 11 formed in its center in axial alignment with the holes 9 and 10.

The last named hole 11 has a stop member 12 mounted to swing on a pin 13 in parts 4 and 8, and normally held over said hole by means of a spring member 14.

The part mounted rigidly on the motor is shown at 15 and has its end portions rolled into pins as shown at 16 and 17 that slide readily and easily into holes 9 and 10.

It being assumed that the part 1 is fixedly mounted in the desired position, and the part 15 fixedly mounted on a motor, the stop member 12 is moved to completely uncover the hole 11 by pressing down on the end 12a. The pin 17 formed

2

on one end of member 15 is now thrust through the hole 10 and the uncovered hole 11 until pin 16 clears the edge of part 3 and is allowed to slip into the hole 9 and into contact with the opposing end portion 7. When this final position of the motor is achieved the pin 17 has dropped back through the hole 11 and stop member 12 is allowed to return to its normal position as shown in Figure 3, and holds the motor against longitudinal movement and displacement on its mounting.

While I have shown and described only the preferred form of my invention, it should be understood that various changes and modifications may be made within the scope of the appended claims without departing from the spirit of the invention.

I claim:

1. A device of the character described comprising, an elongated element fixedly mountable on a support and having similarly turned end portions having holes formed therein, one end portion having an extension to form a stop in spaced relation to said hole, and the other end portion having an extension provided with a hole in axial alignment with the first mentioned holes, and an elongated member having pinlike members extending from its opposite ends and adapted to pass through said holes in said first mentioned element, said member being mountable on a motor.

2. The structure set forth in claim 1 wherein the hole in the extension on the second mentioned end is normally blocked by a resiliently mounted stop member.

JAWN R. HALL.
